UNITED STATES PATENT OFFICE.

CHARLES A. PEAK, OF EVANSVILLE, INDIANA, ASSIGNOR OF ONE-HALF
TO L. AMIET, OF HENDERSON, KENTUCKY.

HYDRANT.

No. 836,400.

Specification of Letters Patent.

Patented Nov. 20, 1906.

Application filed May 29, 1905. Serial No. 262,861.

To all whom it may concern:

Be it known that I, CHARLES A. PEAK, a citizen of the United States, residing at Evansville, in the county of Vanderburg and State of Indiana, have invented a new and useful Hydrant, of which the following is a specification.

This invention relates more particularly to improvements in that class of hydrants wherein the valve is located below the frost-line and means are provided for permitting the escape of water in the pipe outside the valve when said valve is closed.

The principal object is to provide a novel and exceedingly simple mechanism which will permit the free escape of the water in the delivery-pipe when the waste-passage is closed and will close the valve when the valve is opened, the parts being entirely accessible and not liable to derangement.

The preferred embodiment of the invention is illustrated in the accompanying drawings, wherein—

Figure 1 is a view in elevation of the improved structure. Fig. 2 is a vertical longitudinal sectional view therethrough. Fig. 3 is a cross-sectional view. Fig. 4 is a detail bottom plan view of the valve-casing, showing the vent opened.

Similar reference-numerals designate corresponding parts in all the figures of the drawings.

In the embodiment illustrated a boxing is employed comprising a base 5, having a waste opening 6 and a body 7 secured on said base. Within this boxing is located a casing 8, provided with depending supports 9, secured to the base 5. The casing has an inlet 10, into which is threaded a supply-pipe 11, that passes through one end of the boxing. The other end of the casing is upturned and forms an outlet 12, in which is screwed a delivery-pipe 13, that extends through the top of the boxing and in the present embodiment terminates at its upper end in an overhanging discharge-spout 14.

A turning-plug 15 is journaled in a suitable seat for it formed in the casing and projects above the same, having a flat-sided lug 16 interlocking with the lower end of an operating-stem 17, the upper end of said stem being provided with a suitable hand-wheel 18. This stem passes through a guide sleeve or tube 19, the lower end of which is threaded into a

boss 20, formed on the top of the boxing, the upper portion of the sleeve or tube being connected to the delivery-pipe 13 by means of a yoke 21. The turning movement of the valve-stem, and consequently of the valve, is limited by a pin 22, operating in a slot 23 in the upper end of the tube 19.

The casing 8 between the turning-plug or valve and the delivery end is provided with a waste-passage 24, located in the lower side of said casing at one side of the plug and seat, said vent being disposed entirely out of alignment with the plug and opening through a depending nipple 25. This waste-passage is disposed directly over the opening 6 in the bottom 5 of the boxing and is controlled by a closure-plate 26, movable to and from a position over the nipple and being secured by suitable means—as, for instance, screws 27—to the lower end of the turning-plug. The closure-plate is disposed longitudinally of an opening 28 in the turning-plug, and thus it will be seen that when the plug is in a position to permit the passage of water through the casing the plate will be located directly over the waste-passage, as illustrated in Fig. 2. Consequently it will be apparent that when the valve is closed the waste-passage will be opened. It is therefore apparent that when the hydrant is opened to permit the passage of water therethrough the waste-passage will be closed against the waste of any material amount of water. When, however, the hydrant is closed, the waste-passage is opened fully and the water in the delivery-pipe and in the outer portion of the casing beyond the valve can freely escape into the boxing and thence through the opening 6 into the ground. The boxing can of course be sunk to any depth desired and thoroughly protects the inclosed casing, forming, moreover, a chamber to permit the free escape of the water from the delivery-pipe.

It will be clear that the structure is very simple and the parts, while not liable to derangement, are entirely accessible should repairs become necessary. It is also to be noted that the valve-plate 26 is disposed exteriorly of the casing, where it can be readily reached, and, furthermore, constitutes means for retaining the plug in its seat, thereby performing a double function.

From the foregoing it is thought that the construction, operation, and many advan-

ages of the herein-described invention will be apparent to those skilled in the art without further description, and it will be understood that various changes in the size, shape, proportion, and minor details of construction may be resorted to without departing from the spirit or sacrificing any of the advantages of the invention.

Having thus described my invention, what I claim as new, and desire to secure by Letters Patent, is—

1. In a hydrant, the combination with a casing having a water passage-way therethrough, a plug-seat disposed transversely of the water passage-way, and a waste-passage also disposed transversely of the passage-way, said waste-passage communicating with the passage-way and having its outer end out of alinement with the plug-seat, of a turning-plug rotatably mounted on the seat and projecting below the casing, and a valve carried by the projecting portion of the plug, and constituting means for retaining the plug in its seat, said valve being located outside of the casing and movable over and from the outer end of the waste-passage.
2. In a hydrant, the combination with a boxing having an opening in its bottom, of a tubular guide connected to the top of the

boxing, a casing located within the boxing above the bottom thereof and having a waste-passage in its lower side that is located over the opening of said boxing, a supply-pipe connected to one end of the casing, a delivery-pipe connected to the other end, a turning-plug journaled in the casing beneath the guide-tube and at one side of the waste-passage, said plug projecting above and below the casing, an actuating-stem for said plug extending downwardly through said tube and connected to the upper projecting end of said plug, and a closure secured to the lower projecting end of the plug outside the casing, and operating in the boxing between the waste-passage and opening, said closure being movable to and from a position over the outer end of the waste-passage when said turning plug is operated, and furthermore constituting means for retaining the plug in the casing.

In testimony that I claim the foregoing as my own I have hereto affixed my signature in the presence of two witnesses.

CHARLES A. PEAK.
